[57] CLAIM

The ornamental design for a conveyor line parts hanger, substantially as shown and described.

DESCRIPTION

FIG. 1 a front perspective view of a conveyor line parts hanger showing our new design;

FIG. 2 is a rear elevational view thereof;

FIG. 3 is a top plan view thereof;

FIG. 4 is a bottom plan view thereof;

FIG. 5 is a side elevational view thereof, the opposite side elevational view being a mirror image of that shown; and

FIG. 6 is a cross sectional view taken along line 6—6 of FIG. 2.

FIG. 1

FIG. 2 6

FIG. 3

FIG. 4

FIG. 5
